United States Patent

Des. 234,767

Patented Apr. 8, 1975

234,767

LOW VOLUME SPRAYING MACHINE

Theodore F. Lenhardt and Edward D. Scheffler, Jr.,
Coloma, Mich., assignors to AG Tec Inc., Indianapolis,
Ind.

Filed Feb. 22, 1973, Ser. No. 334,619

Term of patent 14 years

Int. Cl. D23—01

U.S. Cl. D23—18

Fig. 1

Fig. 2

Fig. 3

Fig. 4

Fig. 5

FIG. 1 is a left side elevational view of a low volume spraying machine showing our new design.

FIG. 2 is a right side elevational view thereof.

FIG. 3 is a top plan view thereof.

FIG. 4 is a rear view thereof.

FIG. 5 is a front view thereof.

The bottom is without ornamentation.

We claim:

The ornamental design for a low volume spraying machine, as shown and described.
